UNITED STATES PATENT OFFICE.

THOMAS J. LITTLE, JR., OF DETROIT, MICHIGAN, ASSIGNEE TO CADILLAC MOTOR CAR COMPANY, OF DETROIT, MICHIGAN, A CORPORATION OF MICHIGAN.

HYDROCARBON MOTOR.

Application filed May 28, 1917. Serial No. 171,433.

To all whom it may concern:

Be it known that I, THOMAS J. LITTLE, Jr., a citizen of the United States, and resident of Detroit, Wayne County, State of Michigan, have invented certain new and useful improvements in Hydrocarbon Motors, of which the following is a specification.

This invention relates to hydrocarbon motors, and more particularly to improvements in means for providing a satisfactory explosive mixture or gas therefor.

One of the objects of this invention is to provide a hydrocarbon motor with an improved arrangement and disposition of the gas conduit and distributing passages, wherein the impedance to the flow of gases is reduced to a minimum.

Another object of this invention is to provide improved means for maintaining a hydrocarbon motor induction pipe at a proper temperature and to prevent condensation of the gases therein.

Another object of this invention is to so arrange the relation of the carburetor, the induction pipe and the intake passages of a hydrocarbon motor that the fuel, air and explosive mixture are at all times travelling in the same general direction. In my preferred form, this direction is downwardly, so that the tendency to precipitate the hydrocarbon fuel gases is reduced to a minimum, and, on the other hand, any gas which is precipitated in the form of liquid is carried on to the interior of the motor.

Another object of this invention is to provide a multi-cylinder motor with a gas carbureting and distributing system having an improved throttle, which permits a more uniform distribution of gases to various cylinders, while the motor is operating under different throttle conditions.

Another object of this invention is to provide a motor with a carbureting system, having means for supplementing the ordinary supply of air with an auxiliary source under pressure, for increasing the high speed operation of the motor particularly.

Another object of this invention is to provide a hydrocarbon motor carbureting system with improved devices for controlling the quality and quantity of the mixture produced therein.

Another object of this invention is to generally improve the construction, operation

and efficiency of fuel mixture producers and distributors for hydrocarbon motors.

These and various other objects will more clearly appear from the following description taken in connection with the accompanying drawings which form a part of this specification and in which:

Figure 1 is a fragmentary end elevation, with portions in section, of a V type hydrocarbon motor and a preferred form of my carbureting and gas distributing system;

Figure 2 is a side elevation, partly in section, taken substantially at right angles to Figure 1, of my carbureting and gas distributing system;

Figure 3 is a plan view of the central parts illustrated in Figures 1 and 2, substantially on the line 3—3 of Figure 1, with the float chamber and its associated parts removed; and

Figure 4 is a plan view of the upper carbureting unit with the dome removed substantially on the line 4—4 of Figure 1, with a portion of the float chamber cover broken away.

Referring to the drawings, 10 illustrates a pair of cylinder blocks suitably mounted in V relation, each having formed in its inner faces, an intake port 11 and an exhaust port 12. It will be noted that arranged adjacent the upwardly inclined mouths 13 of the intake ports are poppet valve members 14, which are adapted to be closed by means of spring devices 15' and may be opened in any well known manner.

The lower or gas conducting and distributing unit which is sometimes known as a gas intake or induction pipe, in the illustrated form, comprises the substantially vertical upwardly extending long leg 15, having formed at its upper end an intake port 16 and at its lower end, a pair of laterally extending downwardly inclined distributing branches 17, the outlets of which are adapted to register with the intake ports 11 and 12 to be detachably secured in position as by bolts 18. Thus it will be seen I have provided a gas conducting and distributing passage of substantially V shape, the long leg extending upwardly.

The conduit is provided with a heating jacket 19, having oppositely disposed laterally extending arms 20, each having an intake port 21 in register with an exhaust port 12 of the cylinders. These arms are

adapted to be bolted into position as by bolts 22; and an outlet port 23 is formed in the jacket at its lower end adjacent the dividing point 24, between the branches, i. e. 5 at the apex of the Y.

For the purpose of better heating the gases as they are deflected at the lower end of the conduit and distributed into the branches 17 and for preventing the formation 10 of any condensation at this point, I have provided means for maintaining a higher temperature at this point by arranging in the jacket, an electrical element which may be of any well known form, but 15 which is illustrated as comprising a pair of insulating plates 25, preferably of mica, a heating element 26 and a clamping plate 27, held in position as by stud screws 28. Electric current may be led into the heating 20 element 26 by an electrode 29 and the opposite end of the circuit may be closed by grounding the same as by connecting it to the clamping plate.

A throttle valve in the form of a sleeve 25 30 is adapted to be slidably arranged in the leg 15 and formed with a double V shaped lower end 31 for conforming with the apex 32 of the conduit distributing branches 17. This valve may regulate the communication 30 of the lower end of the leg 15 with each of the distributing branches 17. The throttle valve is adapted to be operated, as will be described hereinafter, by means of a rod 33 which is preferably connected there- 35 to as by rivets 33' adjacent its upper end.

The upper end of the leg 15 is provided with a flared cup portion 34 which is formed with a flange 35 on which a float chamber shell 36 is adapted to be suitably mounted. 40 The shell 36 is provided centrally thereof with an re-entrant tubular portion forming a mixing or Venturi tube 37. A cover member 38 is adapted to be arranged in position on the shell 36 and the cover, shell, and 45 cup portion 34 are all adapted to be secured together as by bolts 39 shown in Figure 2.

It will be noted that the central portion of the cover member 38 is provided with a flared mouth 40, adapted to be fitted over 50 the upper end of the Venturi tube and forming the intake of this tube. The outlet port 41 of the venturi being formed at its lower end. The cover 38 is formed with a fuel feed nipple 42, communicating by means of 55 a passage 43 with a valve chamber 44 which is adapted to be controlled by means of a needle valve 45 and by means of a float 46 which is pivoted as at 47 on a lug formed integral with the shell 36. This float valve 60 mechanism is adapted to normally maintain a predetermined level of fuel in the chamber 36 and therefore in the passages 48 which communicate therewith at their lower end and lead to a plurality of radially arranged 65 nozzles 49 which project laterally into the

Venturi tube 37 adjacent its upper end. I provide a number of these nozzles to which the fuel is uniformly fed for the purpose of supplying the fuel in an extremely fine spray under normal operation.

70

It will be noted that the float shell 36 is provided with a number of cored out passages, one of which is in communication at its lower end, with the fuel and forms a stand pipe 50 in which the fuel is normally 75 maintained at the same level as that of the fuel in the chamber proper. A plunger member 51, in the form of a piston, is adapted to be very loosely fitted in this pipe and is provided with an upwardly extending rod 80 which is adapted to be pivoted as at 52 to one arm 53 of a bell crank, which is trunnioned as at 54 on a link 55 which is similarly trunnioned as at 56 on the shell 36. The upper end of the throttle operating rod 33 85 is coupled as at 57 to the extreme outer end of the arm 53 of the bell crank, so that as the throttle valve 30 is opened by lifting it upwardly, the piston member 51 is moved in the same direction. If it happens that 90 the opening movement of the throttle is comparatively rapid, much of the fuel which rests upon the upper part of the plunger 51 will be carried up to the port 58 shown in Figure 4, from which it will flow down the 95 passage 59 and discharge into the carburetor beside the Venturi tube 37 and above the upwardly extending long leg 15. In other words, with this arrangement the supply of fuel to the carburetor is increased, upon the 100 rapid opening action of the throttle independently of the flow from the nozzles 49.

A dome shaped cover or shell 61 having a plurality of primary air ports 62 is adapted to be arranged over the top of the float chamber cover 38 and serves as a housing for the open end of the Venturi tube and the throttle operating devices. It will be noted that this dome is provided with a slotted portion 63 through which the arm 53 110 of the bell crank lever projects.

The dome shell is provided at its upper end with an opening 64 into which is adapted to be introduced a valve shell 65 which has a threaded contracted portion 66 to which 115 may be secured a retaining collar 67. A tapered valve plug 68 having a jet portion 69 is adapted to be rotatably mounted in the chamber 65, which in turn is arranged to be connected with any suitable supply of air 120 under pressure and when the port 70 of the jet 69 is brought into register with the supply passage 71, air under pressure is blown into the inlet of the Venturi tube 37. This pressure air valve is adapted to be suitably 125 operated in any well known manner.

It is to be noted that the cup portion 34 of the leg 15 is provided with a plurality of auxiliary air ports 72, which are adapted to be controlled by a sleeve 73 which is slidably 130

mounted on the exterior of the upper end of the leg 15, and is provided with an outwardly flange 74 for opening and closing the port 72 proper. It will be understood that as the pressure within the carburetor decreases, atmospheric pressure will lift the flanged portion 74 of the valve and thus admit secondary air to the interior thereof. The action of this valve member may be regulated by means of a bifurcated member 75, trunnioned in the cup portion 34 of the leg 15 as at 75' and provided with a pair of forks 76, which rest against the flange 74 of the sleeve valve 73. The opposite end of the member 75 is provided with an arm 77, the extreme end of which is adapted to abut against a spring 78 which is adjustably mounted on a threaded pin 79. A rod 80 is adapted to be introduced through a cored out passage 81, shown in Figure 4, with its lower end resting upon a lug 82 inturned from one of the arms 76. A cam lug 83 is formed on a bow shaped spring member 83' which is arranged on the plug 68 and secured in position by the nut 84, in such a manner that the valve plug 68 may be turned in one direction without admitting the pressure of air to the jet and yet moving the cam lug 83 over the upper end of the rod 80 to maintain the lower end against the arm 76, thus choking off the supply of auxiliary air, and for high speed work, the valve plug 68 may be moved in a reverse direction, relieving the auxiliary air valve 35 and also admitting a supply of air under pressure to the jet 69 for leaning the mixture produced by the carburetor.

It will be noted that the bow shaped spring 83' will always exert a spring pull on the valve plug 68, thus keeping the valve air-tight.

With the construction which I have described, the mixture of hydrocarbon fuel and air is effected at the uppermost parts of the carbureting system, and all forces, including gravity, tend to sweep the gases downwardly into the intake port of each of the blocks with only a single turn, therefore the impedance to the flow of mixture is reduced to a minimum, and, also, it will be seen that the tendency to precipitate or condense the gases is likewise reduced to a minimum. In any event if condensation is formed, it will be carried to the lower wall of the induction pipe where the temperature is maintained comparatively high by means of the electrical heating elements. The heating effect of this element may be regulated in any well known manner and the flow of exhaust gases through the conduit jacket may be likewise controlled.

While I have described and will specifically claim, what I deem to be a preferred form of my invention, it will be obvious to those skilled in the art that various modi-

fications and changes may be made without departing from the spirit and scope hereof.

Having thus described my invention, what I claim and desire to secure by Letters Patent is:

70

1. The combination with an internal combustion engine, of a gas intake conduit having an upwardly extending main passage, and a plurality of branches leading from said main passage adjacent the lower end thereof; means for heating said passage; and an auxiliary heating device located adjacent the dividing point of said branches where they lead off from said main passage.

2. The combination with an internal combustion engine, of a gas intake conduit of substantially Y shape comprising an upwardly extending main leg and a pair of intersecting downwardly inclined branches, and means for highly heating the apex of the Y.

3. The combination with an internal combustion engine, of a Y shape jacketed conduit having an upwardly extending main leg provided with an intake port at its upper end, and with a pair of laterally extending downwardly inclined branches at its lower end, and means for providing a greater heating of the conduit walls adjacent the dividing point of said branches.

95

4. The combination with an internal combustion engine, of an intake conduit comprising a substantially vertical main leg having an intake port at its upper end, and a plurality of laterally extending downwardly inclined branches, said conduit being provided with a heating jacket, and means for maintaining a relatively higher temperature in said conduit adjacent the dividing point of said branches.

105

5. The combination with an internal combustion engine, of an intake conduit comprising a substantially vertical main leg having an intake port at its upper end, and a plurality of laterally extending downwardly inclined branches, said conduit being provided with a heating jacket, means for maintaining a relatively higher temperature in said conduit adjacent the dividing point of said branches, and an electrical heating element arranged adjacent the dividing point of said branches.

110

6. The combination with an internal combustion engine, of a gas intake conduit comprising a substantially vertical upwardly extending main leg having an intake port at its upper end and a pair of laterally extending downwardly inclined branches, and valve means for regulating the communication of said leg with said branches.

125

7. The combination with an internal combustion engine, of a gas intake conduit comprising a substantially vertical upwardly extending main leg having an intake port at its upper end and a pair of laterally extend-

130

ing downwardly inclined branches, and a valve member for varying the communication of each of said branches with said main leg.

5. 8. The combination with an internal combustion engine, of a gas intake conduit comprising a substantially vertical upwardly extending main leg having an intake port at its upper end and a pair of laterally extending downwardly inclined branches, and a sleeve valve member for varying the communication of the lower end of said leg with the upper end of each of said branches.

9. The combination with an internal combustion engine, of a gas intake conduit comprising a substantially vertical upwardly extending main leg having an intake port at its upper end and a pair of laterally extending downwardly inclined branches, and a 20 reciprocal sleeve valve arranged in said leg and adapted to vary the communication of the lower end thereof with the upper end of each of said branches.

10. The combination with an internal combustion engine, of a gas intake conduit comprising a substantially vertical upwardly extending main leg having an intake port at its upper end and a pair of laterally extending downwardly inclined branches, and a 30 sleeve valve slidably arranged in said leg and having a curved lower end for varying the communication of the lower end of said leg with each of said branches.

11. The combination with an internal combustion engine comprising a pair of cylinder blocks arranged in V relation and each having an intake port and an exhaust port, of a detachable conduit arranged therebe-

tween, comprising an upwardly extending substantially vertical main leg having an intake port at its upper end and a pair of laterally extending downwardly inclined branches at its lower end, the outlet of each of said branches being connected with one of said inlet ports, said conduit being provided with a jacket having laterally extending intake ports each connected with one of said exhaust ports, said jacket also having an outlet port formed therein adjacent the dividing point of said branches. 50

12. The combination with an internal combustion engine, of a gas intake conduit comprising a substantially vertical upwardly extending main leg, having an intake port at its upper end and a pair of laterally extending downwardly inclined branches connected at its lower end, said conduit being provided with a jacket having means for introducing exhaust gas therein adjacent the upper end of said leg and for discharging it from said conduit adjacent the dividing point of said branches. 55

13. The combination with an internal combustion engine, of a gas intake conduit comprising a substantially vertical upwardly extending main leg having an intake port at its upper end and a pair of laterally extending downwardly inclined branches connected with its lower end, said conduit being provided with a jacket having means for introducing exhaust gas therein adjacent the upper end of said leg, and a heating element arranged in said jacket adjacent the lower walls of said branches. 65 70

In testimony whereof I affix my signature. 75
THOMAS J. LITTLE, JR.
